UNITED STATES PATENT OFFICE.

HERMANN HOFFMEISTER, OF GLIESMARODE, NEAR BRUNSWICK, GERMANY, AS
SIGNOR TO GRIMME, NATALIS & CO., AKTIENGESELLSCHAFT, OF BRUNSWICK, GER-
MANY, A CORPORATION OF GERMANY.

CALCULATING MACHINE.

Application filed October 20, 1924, Serial No. 744,789, and in Germany October 27, 1923.

My invention relates to improvements in calculating machines, and more particularly to means for shifting the carriage or slide which carries the setting or registering mechanism which means comprises a lever mounted to rock within a horizontal plane and adapted, when rocked to the right or left, to unlock the carriage and to throw a pawl into engagement with a stop member and thus ensures displacement of the carriage a distance corresponding to the distance of adjacent numeral wheels. The object of the improvements is to provide mechanism of this type by means of which 15 the carriage may be shifted a distance corresponding to a plurality of orders of the numeral wheels without the necessity of a stop for the fingers, and without the pawls sliding along the stops when shifting the 20 carriage. With this object in view, the operating lever which carries the pawls for imparting step-by-step movement to the carriage is mounted so as to be shiftable on its pivot bolt for throwing the pawls into and 25 out of position for engagement with the stops.

Two embodiments of the invention are shown in the accompanying drawing in which the same reference characters are 30 used in all the views to indicate corresponding parts. In said drawing,

Fig. 1, is an elevation, partly in section, showing a calculating machine provided with my improved shifting mechanism,

Fig. 2, is a detail view looking from the right in Fig. 1 and showing the hand piece of the operating lever and the slot formed in the front wall of the machine casing,

Fig. 3, is a bottom view on an enlarged 40 scale showing the operating mechanism,

Fig. 4 is an elevation similar to Fig. 1 and showing a modification of the shifting mechanism, and

Fig. 5 is a bottom view on an enlarged 45 scale showing the shifting mechanism illustrated in Fig. 4.

In the example shown in Figs. 1 to 3 the calculating machine comprises a casing 25, the bottom plate 26 of which is provided with guide ways 27, 28 for the base plate 1 of the carriage 29. Between two pairs of pins 2, 2 and 3, 3 secured to the bottom side of the base plate 1 of the carriage a latch or slide 5 is guided of which slide a nose 6

is normally in locking engagement with a 55 rack 7 provided on the bottom plate 26 of the machine casing. A spring 4 acting on the slide 5 tends to force the same rearwardly to bring the nose 6 into engagement with the rack 7. To the bottom side of the 60 base plate 1 of the carriage is secured a pin 9 which passes through a slot 8 of the slide 5 and a slot 16 formed in a T-shaped rockable operating lever 10 carrying at each of its ends, a pawl 13 acted upon by a spring 65 12 and located between stops 14 and 15 depending from the lever 10. The pawls 13, 13 are adapted to engage a rack 20 provided on the bottom plate 26. On pins 17 secured to the bottom side of the base plate 1 two 70 slide or latch-shifting levers 18 are rockingly mounted which bear on shoulders 19 formed on the slide 5, and which are adapted to engage the stops 14 depending from the lever 10.

The operation of the mechanism is as follows: When rocking the lever 10 in the direction of the arrow X shown in Fig. 3 the stop 14 depending from the right hand arm of the lever 10 rocks the adjacent lever 18, 80 which therefore acts on the shoulder 19 of the slide 5 and retracts the nose 6 out of engagement with the rack 7 and thus releases the carriage 29 from the bottom plate 26 of the casing. Simultaneously the pawl 13 mounted on the left hand arm of the lever 10 is thrown into engagement with the rack 20. When further pressure is exerted on the hand piece 11 the carriage is shifted to the right, until the left-hand pawl 13 85 strikes against the left hand stop 15, whereupon further movement of the carriage is impossible. The distance between the stops 14 and 15 corresponds to the distance between two adjacent numeral wheels. When 90 the lever 10 is released the parts are returned into initial position by the action of the spring 4 through the intermediary of the slide 5 and the levers 18 on the stops 14, 15, whereupon the spring 12 rocks the pawl 13 95 into the position shown in Fig. 3 in which it bears on the stop 14.

For shifting the carriage to the right or left a distance corresponding to a plurality of orders of the numeral wheels the lever 10 is pushed inwardly by pressing on the finger piece 11, so that the stops 14 retract the slide 5 out of engagement with the rack 100

7 through the intermediary of the levers 18, whereupon the carriage can be freely shifted any distance to the right or left.

In the modification shown in Figs. 4 and 5 the rack 20¹ performs the function of the racks 7 and 20 of the example shown in Figs. 1 to 3, by providing stops also for the nose 6¹ of the slide 5¹. The general arrangement of the mechanism is similar to the one described with reference to Figs. 1 to 3. However, the slide 5¹ is reversed as compared to the slide 5, and the nose 6¹ is at the front end of the slide and in position for engagement with the rack 20¹, and the spring 4¹ tends to push the slide in forward direction. To the lever 10¹ two pins 21 are secured, which are in position to bear on levers 22 mounted to rock on pins 30 secured to the base plate 1¹ of the carriage.

For shifting the carriage one step to the right the finger piece 11¹ is pressed to the right and in the direction of the arrow y shown in Fig. 5. Thereby the pin 21 located at the right of the slide 5¹ acts on the slide 25¹ through the intermediary of the lever 22 so as to retract the nose 6¹ away from the rack 20¹. Simultaneously the left hand pawl 13¹ engages in the rack 20¹ and permits the carriage to be shifted one step in the manner described with reference to Figs. 1 to 3. When the finger piece 11¹ is released the parts are returned into the position shown in Fig. 5 by the spring 4¹. If it is desired to shift the carriage a distance corresponding to several orders of the numeral wheels, the finger piece 11¹ is first pushed inwardly. Thereby both pins 21 act on the levers 22 and push the same against shoulders 31 of the slide 5¹ thus retracting the nose 6¹ away from the rack 20¹, whereupon the carriage is free to be shifted.

Preferably the dimensions of the levers 18 and 22 are such that a slight rocking or rectilinear movement of the lever 10 or 10¹ is sufficient to retract the nose 6 or 6¹ out of engagement with the rack 7 or 20¹.

While in describing the invention reference has been made to particular examples embodying the same I wish it to be understood that my invention is not limited to the constructions shown in the drawings, and that various changes may be made in the general arrangement of the apparatus and the construction of its parts without departing from the invention.

I claim:-

1. In a calculating machine or the like embodying a casing and a carriage slidable in said casing, a latch for securing the carriage in adjusted positions in said casing, an operating member mounted on said carriage for sliding movement and also for rocking movement, means operable by either a sliding or rocking movement of said operating member to retract said latch, and

means associated with said operating member and engageable with said casing in the rocking movement of the operating member to limit the advancing movement of said carriage.

2. In a calculating machine or the like embodying a casing and a carriage slidable in said casing, a latch normally securing said carriage against movement, an operating member, means on the carriage on which said operating member is fulcrumed for rocking and sliding movement and on which said latch is also slidable, means operable by either the rocking movement or the sliding movement of said operating member for releasing said latch, and means associated with said operating member and caused by the rocking movement of said operating member to engage said casing and limit the advancing movement to said carriage.

3. In a calculating machine or the like embodying a casing and a carriage slidable in said casing, an operating member mounted on said carriage for sliding movement and also for rocking movement, a rack carried by said casing, a latch normally securing said carriage against movement in said casing, a pawl carried by said operating member and engageable with said rack when said operating member is rocked to limit advancing movement of said carriage, and a lever adapted, when rocked, to engage and retract said latch, said operating member when either rocked or given a sliding movement, engaging with and rocking said lever.

4. In a calculating machine or the like embodying a casing and a carriage slidable in said casing, an operating member having a slot, a pin mounted on said carriage and working in said slot to permit slidable movement of said operating member and on which said operating member may rock in opposite directions, a rack carried by said casing, a pair of pawls carried by said operating member, one of said pawls adapted to engage said rack when said operating member is rocked in one direction to limit advancing movement of said carriage in that direction and the other of said pawls adapted to engage said rack when said operating member is rocked in the opposite direction to limit advancing movement of said carriage in that direction, a latch normally securing said carriage against movement, and a pair of levers adapted, when rocked, to engage and retract said latch, said operating member, when rocked in either direction, engaging and rocking one of said levers and, when given a sliding movement, engaging and rocking both of said levers.

5. In a calculating machine or the like, a casing, a carriage slidable in said casing, a T-shaped operating lever having a slot in its vertical arm, a pin mounted on said carriage and extending into said slot to per-

mit sliding movement of said lever and on which said lever is fulcrumed for rocking movement, a sliding latch for securing said carriage in adjusted positions in said casing, a pair of levers, one mounted at each side of said latch and adapted, when rocked, to engage and retract said latch, a rack carried by said casing, a pawl mounted on each of the horizontal members of said T-shaped lever and adapted, respectively, when said T-shaped lever is rocked in opposite directions, to engage said rack and limit advancing movement of said carriage, said T-shaped lever adapted, when rocked in one direction, to engage and rock one of said pair of levers and, when rocked in the opposite direction, to engage and rock the other of said pair of levers, said T-shaped lever, when given a sliding movement, engaging and rocking both of said pair of levers.

10 In testimony whereof I have affixed my signature.

DR. ING. HERMANN HOFFMEISTER.
